Primary Examiner—Kay H. Chin

Attorney, Agent, or Firm—Standley & Gilcrest

[57] **CLAIM**

The ornamental design for a kickboard, as shown and described.

DESCRIPTION

FIG. 1 is a top plan view of a kickboard showing my new design;
FIG. 2 is a bottom plan view thereof;
FIG. 3 is a left side elevational view thereof, the opposite side view being a mirror image of that shown;
FIG. 4 is a front elevational view thereof;
FIG. 5 is a rear elevational view thereof;
FIG. 6 is a top perspective view thereof;
FIG. 7 is a bottom perspective view thereof; and,
FIG. 8 is a cross-section view thereof taken along line 8—8 of FIG. 2.

1 Claim, 2 Drawing Sheets
